UNITED STATES PATENT OFFICE.

RICHARD JOHN WALTER DWINNELL, OF MONTREAL, QUEBEC, CANADA, ASSIGNOR TO THE
PERFECT SIMPLEX COMBUSTION COMPANY, OF MONTREAL, CANADA.

SMOKE-CONSUMER.

No. 918,518.

Specification of Letters Patent.

Patented April 20, 1909.

Application filed January 17, 1907. Serial No. 352,819.

To all whom it may concern:

Be it known that I, RICHARD JOHN WALTER DWINNELL, of the city of Montreal, Province of Quebec, Canada, have invented 5 certain new and useful Improvements in Smoke-Consumers; and I do hereby declare that the following is a full, clear, and exact description of the same.

This invention relates particularly to 10 smoke consumers of the type located at the rear of the fire chamber, and it has for its object to provide a device of this nature adapted to thoroughly mix the products of combustion with air during their passage 15 from the space above the fire grate to the space behind the bridge wall and at the same time concentrate the mixture of gases and air at this point in the fire zone, with the result that all inflammable gases are ignited or 20 burned before they enter the tubes.

The invention may be said briefly to consist of the combination and arrangement of parts hereinafter described and pointed out in the claims. For full comprehension, however, 25 of my invention, reference must be had to the accompanying drawings, forming a part of this specification, in which similar reference characters indicate the same parts and wherein—

30 Figure 1 is a longitudinal vertical sectional view of the furnace of a tubular boiler, with my invention applied thereto; Fig. 2 is a sectional view thereof taken on line A A Fig. 1; and Fig. 3 is a similar view to Fig. 1 35 of a modification of my invention. Fig. 4 is a horizontal sectional view taken on line B B Fig. 1.

The forward face of the bridge-wall *b* is concaved as at *c* and the upper edge thereof 40 is extended forwardly as at *d*, while a baffling member is supported by a pier *e* a short distance in advance of the bridge-wall and it presents a rearwardly projecting horizontal rib *f* with its underside concaved as at *g*. An auxiliary grate *k*, formed of a pair of grate 45 sections and constituting a continuation of the main grate *m*, is located beneath the baffling member and extends from the pier to each side of the fire chamber; and a pair 50 of air flues, *n* and *o*, are formed in the rear wall of the furnace beneath and communicating with the said auxiliary grates.

To meet certain requirements the baffling member is constructed in the form of a 55 twyer, in that it is made hollow and down-

wardly tapering with a discharge opening in its lower end and it is fed with heated pure air by flues *q* in the side walls of the furnace such flues communicating with the ash pit at points *r* within the flues *n* and *o*.

The rib *f* and forward extension *d* of the bridge-wall form a contracted passage for the products of combustion and air mixed, and a twyer-like effect is produced thus intensifying the heat at this point and rendering the consumption of the inflammable gases and small particles of carbon carried thereby, more perfect.

Under ordinary conditions the air admitted through the auxiliary grate sections to 70 the chamber presented by the concavity in the bridge-wall is sufficient to insure perfect combustion, but under certain conditions, for instance where it is the practice to burn a very volatile fuel, the air supplied through 75 the baffle increases the efficiency of the furnace.

What I claim is as follows:—

1. The combination with the fire chamber and bridge wall of a furnace, of a transverse 80 baffle extending downwardly from the roof of the fire chamber and adjacent to the bridge wall, a fire grate extending between the front of the fire chamber and bridge wall and beneath the baffle and presenting a passage therebetween and the said baffle, and means projecting from the said baffle and contracting the upper portion of the passage between the baffle and bridge wall to less capacity than the lower portion of such passage.

2. The combination with the bridge wall of a furnace, such bridge wall having a concavity in its forward face, of a baffle extending across the furnace adjacent to the bridge 95 wall and having a rib upon its rear side extending parallel to the upper edge of the bridge wall, and means for supplying pure air to the space between the bridge wall and baffle.

3. The combination with the bridge wall of a furnace, such bridge wall having a forward extension along its upper edge, of a baffle extending across the furnace adjacent to the bridge wall and having a rib upon its rear side extending parallel to the upper edge of the bridge wall, and means for supplying pure air to the space between the bridge wall and baffle.

4. The combination with the bridge wall 110

- of a furnace, such bridge wall having a concavity in its forward face, and a forward extension along its upper edge of a baffle extending across the furnace adjacent to the bridge wall and having a rib upon its rear side extending parallel to the upper edge of the bridge wall, and means for supplying pure air to the space between the bridge wall and baffle.
- 10 5. The combination with the bridge-wall of a furnace, such bridge-wall having a concavity in its forward face, of a baffle extending across the furnace adjacent to the bridge wall and having a rib upon its rear side extending parallel to the upper edge of the bridge wall, and a pair of flues formed in the rear wall of the furnace for supplying pure air to the space between the bridge wall and baffle.
- 15 6. The combination with the bridge wall of a furnace of a hollow baffle adjacent to the said bridge wall and consisting of a pair of downwardly converging plates and a cover plate; a baffle-wall extending upwardly from the said hollow baffle, flues supplying air through the baffle to the space between the latter and the bridge wall, and means supplying air directly to the said space.
- 20 7. The combination with the bridge wall of a furnace of a hollow baffle adjacent to the

said bridge wall, flues supplying air through the baffle to the space between the latter and the bridge wall, and means supplying air directly to the said space, and means for contracting the passage from the said space, such means consisting of a forward extension upon the top edge of the bridge wall and a rearwardly extending horizontal rib upon the baffle.

8. The combination with the bridge wall of a furnace, of a hollow baffle adjacent to the said bridge wall and consisting of a pair of downwardly converging plates and a cover plate; a baffle-wall extending upwardly from the said hollow baffle, flues supplying air through the baffle to the space between the latter and the bridge wall, and means supplying air directly to the said space, and means for contracting the passage from the said space consisting of a forward extension upon the top edge of the bridge wall and a rearwardly extending horizontal rib upon the baffle.

In testimony whereof, I have signed my name to this specification, in the presence of two subscribing witnesses.

RICHARD JOHN WALTER DWINNELL.
